United States Patent

Des. 235,804
Patented July 8, 1975

235,804

MOTION PICTURE PROJECTOR-VIEWER

Alex J. Procop, 20731 Prairie St.,
Chatsworth, Calif. 91311

Filed Aug. 22, 1973, Ser. No. 390,397

Term of patent 14 years

Int. Cl. D16—02

U.S. Cl. D61—1 N

Fig. 1

Fig. 2

Fig. 3

Fig. 4

Fig. 5

FIG. 1 is a right front perspective view of a motion picture projector-viewer showing my new design;

FIG. 2 is a top plan view thereof;

FIG. 3 is a front elevational view thereof;

FIG. 4 is a rear elevational view thereof;

FIG. 5 is a left side elevational view thereof.

I claim:

The ornamental design for a motion picture projector-viewer, substantially as shown and described.
